UNITED STATES PATENT OFFICE.

JOSEPH R. BOWEN, OF HOLLYWOOD, CALIFORNIA, ASSIGNOR TO CLEAN-BE-TWEEN
TOOTH BRUSH COMPANY, OF ST. LOUIS, MISSOURI, A CORPORATION OF DELAWARE.

DESIGN FOR A TOOTHBRUSH HANDLE.

Application filed December 27, 1927. Serial No. 24,652. Term of patent 14 years.

To all whom it may concern:

Be it known that I, JOSEPH R. BOWEN, a citizen of the United States, and a resident of Hollywood, Los Angeles County, California, have invented a new, original, and ornamental Design for a Toothbrush Handle, of which the following is a specification, reference being had to the accompanying drawing, forming part thereof.

Fig. 1 is a plan view of a tooth-brush handle, showing my new design; and Fig. 2 is an elevational view of the same.

I claim:

The ornamental design for a tooth-brush handle, as shown.

JOSEPH R. BOWEN.
